STABLE DISPERSIONS OF FATTY AMINE
ACID SALTS

Thomas H. Lentz, St. Louis Park, and Joseph W. Opie and David E. Terry, Minneapolis, Minn., assignors to General Mills, Inc., a corporation of Delaware

No Drawing. Application October 5, 1955
Serial No. 538,762

4 Claims. (Cl. 252—311)

This invention relates to novel compositions containing fatty amine salts in admixture with other constituents that are easily dispersible in water. Furthermore, the compositions of this invention upon dispersion form compositions stabilized to a degree heretofore unobtainable.

Fatty amines are long chained aliphatic amines. Their preparation from fatty acids by reacting the fatty acids with ammonia to produce the corresponding nitrile and subsequent reduction of the nitrile to amine is a well-known commercially successful process. Likewise, the use of fatty amines and their salts as aqueous dispersions in the ore flotation industry and as corrosion inhibitors is well known and practiced extensively.

Although used commercially as shown above the aqueous dispersions of fatty amines and their salts presently employed have disadvantages of varying degree and kind. For instance, the accepted practice is to prepare 5 to 10% aqueous concentrates prior to their actual use. Previously it was necessary to use hot water (60 to 100° C.) and extended periods of stirring of from 10 to 24 hours in the preparation of these concentrates. Even after this laborious preparation it was not uncommon to have the dispersions "break" upon standing or dilution with cold water. By "break" we refer to separation of the dispersion into two phases. For example, when cold water is used to dilute the concentrate, the fatty amine salt frequently separates into stringy, insoluble curds.

It is an object of this invention to set forth various compositions containing fatty amine acid salts which are readily dispersible in water.

Another object of this invention is to disclose various aqueous dispersion of fatty amine acid salts that are relatively stable in water.

It has now been discovered that mixtures of fatty amine acid salts and non-polar organic compounds, such as kerosene and fuel oils, fulfill these objects.

Additional advantages and objects of this invention will become apparent to those familiar with the various applications in which aqueous dispersion of fatty amine acid salts are employed.

The fatty amines envisioned by this invention are those derived from fatty acids. These acids are long-chained high molecular aliphatic carboxylic acids either saturated or unsaturated. The principal source of these fatty acids are from naturally occurring fats and oils in animals and plants. Illustrative of these fats and oils are tallow, greases, soybean oil, corn oil, cottonseed oil, palm oil, etc. The bulk of these acids have from 8 to 22 carbon atoms with a preponderance of acids having 18 carbons such as stearic, oleic, linoleic and linolenic acid. Generally speaking the primary fatty amines will have the same number of carbon atoms as the acid or acids used as a starting material, that is from 8 to 22 carbon atoms.

The acid salts of the fatty amines are prepared by mixing an appropriate acid with the fatty amines while they are in a molten state. Both organic and inorganic

2

acids are suitable for this purpose. Hydrochloric and acetic acid are two acids commonly used and acetic acid is preferred. Although fully neutralized amines are preferred, mixtures containing small amounts of free amine may be employed without negating the full benefits of this invention.

Non-polar organic compounds of the type envisioned by this invention are derived from petroleum. They are primarily mixtures of aliphatic hydrocarbons composed of 85 to 88% carbon and 12 to 15% hydrogen. More particularly, these compounds derived from petroleum have a boiling point in the range of 200 to 360° C. They are commonly referred to as fuel oils. Arbitrary numbers 1 through 6 have been assigned to various fractions and mixtures of these compounds. Number 1 fuel oil is the same as kerosene. Number 2 fuel oil is used for domestic heating. Number 4 to 6 fuel oils are light to heavy industrial oils. All of the above fuel oils are adequate for the purposes of this invention.

These non-polar organic compounds are by their very nature immiscible in water. With this in mind it is entirely unexpected that they would increase the rate at which the fatty amine salts disperse in water. It is also unexpected that they should help produce a more stable dispersion. More specifically it has been discovered that as low as 4% of the non-polar aliphatic hydrocarbon may be employed to derive the benefits of this invention. Likewise, it is important that not too much of the non-polar hydrocarbon is utilized. The preferred range for the amount of non-polar hydrocarbon employed is from 4 to 10% by weight. The preferred range of fatty amine salt employed (calculated by difference) is from 96 to 90% by weight.

The mixtures of fatty amine salts and non-polar hydrocarbons described above form stable water dispersions when mixed with water. These dispersions are especially stable when they contain 1 to 10% of the fatty amine salt and non-polar hydrocarbon mixture and 90 to 99% water. The preferred range is 5 to 10% fatty amine salt and non-polar hydrocarbon mixture and 95 to 90% water.

Example 1

In order to measure the dispersion time of technical grade tallow primary amine acetate in water at 65° C., 9 grams of the amine acetate was placed in a 400 ml. beaker and 291 grams of water at 65° C. was added. This mixture was stirred mechanically at a slow rate, which simulated actual preparation conditions in the field. The time required for complete dispersions was 15 to 20 minutes.

Example 2

Technical grade tallow primary amine acetate was mixed with varying amounts of fuel oil number 2. These mixtures were then dispersed in water in the same manner as Example Number 1. Those mixtures of fatty amine and fuel oil containing 3% fuel oil number 2 required 10 minutes to disperse completely. Mixtures containing 10% fuel oil number 2 required 3 minutes for complete dispersion. Mixtures containing 4% fuel oil number 2 dispersed in 3 minutes.

Example 3

A mixture containing 96% technical grade tallow amine acetate and 4% fuel oil number 1 (kerosene) was completely dispersed in water according to the procedure in Example Number 1 in 4 minutes.

Example 4

A 10% dispersion of technical grade tallow amine acetate prepared as in Example 1 was mixed while still hot with 300 ml. of water at 5° C. This resulted in a

2½% solution of amine acetate in cold water. After one hour at 7 to 8° C. without stirring, the amine acetate separated into strings or curds.

Example 5

Technical grade primary tallow amine acetate containing 4% fuel oil number 2 was subjected to the test described in Example Number 4. The 10% dispersion at 65° C. was complete in 3 minutes. Upon standing the 2½% concentration remained homogeneous indefinitely.

Now, therefore, we claim:

1. Composition readily dispersible in water consisting essentially of 90 to 96% by weight of a fatty amine acid salt and 4 to 10% by weight of a non-polar aliphatic hydrocarbon having a boiling range of 200 to 360° C. said fatty amine containing 8 to 22 carbon atoms. 15

2. Composition readily dispersible in water consisting essentially of 90 to 96% by weight of a fatty amine acetate salt and 4 to 10% by weight of a non-polar aliphatic hydrocarbon having a boiling range of 200 to 360° C., said fatty amine containing 8 to 22 carbon atoms.

3. Stable composition composed of 90 to 99% water and 1 to 10% of a mixture composed of 90 to 96% by weight of a fatty amine acid salt and 4 to 10% by weight of a non-polar aliphatic hydrocarbon having a boiling range of 200 to 360° C., said fatty amine containing 8 to 22 carbon atoms.

4. The composition of claim 3 in which the fatty amine acid salt is fatty amine acetate.
